UNITED STATES PATENT OFFICE.

CHARLES R. GURR AND HERBERT TOMLINS, OF LONDON, ENGLAND.

RAILWAY SIGNAL APPARATUS.

SPECIFICATION forming part of Letters Patent No. 643,498, dated February 13, 1900.

Application filed September 21, 1899. Serial No. 731,174. (No model.)

To all whom it may concern:

Be it known that we, CHARLES RICHARD GURR, builder and contractor, a resident of 30 Cranbrook road, Chiswick, and HERBERT 5 TOMLINS, engineer, a resident of 51 Cambridge road, Hammersmith, London, W., England, have invented new and useful Improvements in Railway Signal Apparatus, of which the following is a full, clear, and exact description.

This invention relates to railway-signal-operating mechanism, and has for its object to compensate for variation of length of the wire connections through which the signals are operated and to render impossible the partial or imperfect operation of the signals due to such variation. With this object the wire connections are kept under constant tension and are at all times free to expand or contract, being normally disconnected from the hand-levers by which the signals are operated, the coupling up of a hand-lever with the corresponding connecting-wire being automatically effected at the moment when the 25 signal is to be lowered and the connections between the wire and the lever ceasing immediately the signal is returned to "danger."

Reference is to be had to the accompanying drawings, forming part of this specification, 30 wherein—

Figure 1 is a general view of a signal and of the cabin containing the lever by which it is operated. Fig. 2 is a part-sectional side elevation of the coupling device. Figs. 3, 4, 35 and 5 show a set of three in different positions, Fig. 3 being an end view, and Figs. 4 and 5 sections on line 4-5, Fig. 2, respectively, showing the device in and out of engagement. Fig. 6 is a part-sectional side elevation of a modified construction of the coupling device, the operation being, however, the same in the case of both forms of construction.

The same letters of reference denote like 45 parts in all the figures.

Referring to Figs. 1 to 5, A is the hand-lever in the signal-cabin, and S the signal to be operated in the usual manner—that is to say, the signal is normally held at "danger" 50 by a counterweight B, except when pulled down by the hand-lever, this lever acting through the connecting-wire C, to which, how-

ever, the lever is only temporarily coupled through the medium of the coupling device to the free rack-like member D, with which 55 the wire C is connected. This wire is constantly strained by a weight E, which, acting in opposition to weight B, necessitates the latter being made so much the heavier.

F is the guide-frame of the coupling device, 60 on which a carriage G is fitted to run, said carriage being formed of two cheek-plates provided with friction-rollers g, embracing the guide-frame and also the rack-bar D, which are arranged parallel, the one above the other. 65 The lower arm of the hand-lever A is connected by a link H with the carriage G through the medium of a cross-pin I, on which are mounted rollers J, that work in inclined cam-slots K in the side cheeks of the carriage G. The inclination of the cam-slots corresponds to that of the ratchet-shaped teeth of the rack-bar D, so that immediately the link H is pulled a downwardly-projecting spur L on the head of the link is caused to enter into positive engagement with the rack-bar D. This happens at the very commencement of the movement of the hand-lever A, so that by the continued movement of the latter the motion 70 will be transmitted to rack D and wire C and 75 the signal will be pulled off. On the reverse movement of the hand-lever the signal will first be raised to "danger," and the connection of the hand-lever with the connecting-wire C will then be severed.

The rack is of sufficient length to insure the making of the necessary connection under all possible variations of length of the wire C. The rollers g of the carriage permit free longitudinal sliding movement of the rack-bar 90 D to accommodate the variations of length of the wire C, while they maintain it against any tendency to sag and insure a secure connection of the spur with the rack.

The construction shown in Fig. 6 only differs from the others in that the relative positions of the fixed guide F and rack-bar D are reversed and the cam-guided spur L, (shown in this case engaged with the rack,) by which connection is effected at the proper moment between link H and rack D, is situated between them, the action being precisely similar in all respects.

Although it is obvious that the horizontal

direction of working is preferable, it is not obligatory.

In the working of this apparatus it will be apparent that should the wire C undergo a considerable variation of length in the interval between two operations of the signal which it controls this difference of length will be taken up or allowed for by the weight E, and consequently the spur L on reengaging 10 with the rack D will not engage the same tooth as on the previous occasion.

Having now particularly described and ascertained the nature of the said invention and in what manner the same is to be performed, 15 we declare that what we claim is—

1. The combination with a signal-operating wire under tension and a rack connected to the wire, of a carriage supporting said rack and through which said rack is slideable, said 20 carriage being formed with an inclined slot, a link fitted in said slot and formed with a spur adapted to engage the teeth of the rack when the link moves down in said slot, and means for moving said link, as specified.

2. The herein-described means of allowing 25 and compensating for variations of length of a signal-operating wire, which consists in the combination with a signal-wire, normally disconnected from its operating hand-lever and 30 under a constant tension, of an automatic

connecting and disconnecting device interposed between the hand-lever and the wire, and consisting of two normally-disconnected members adapted to be thrown into connection by the action of cams at the initial movement of the operating hand-lever, the one member being a rack connected to the wire and the other a spur connected to the hand-lever rod and combined with cam-slots in a sliding carriage which have for effect to 35 throw the spur into or out of engagement with the rack and to maintain such condition of engagement and disengagement, substantially as specified.

3. The combination with a signal-operating 40 wire held under tension and a rack connected to said wire, of a guide-frame, a carriage having rollers by which it is mounted to move in said frame, and other rollers on which the rack is movable, said carriage being further provided with inclined slots, a link whose head is provided with rollers movable in said slots, and a spur adapted to engage with the rack, and means for moving said link, as 45 specified.

CHARLES R. GURR.
HERBERT TOMLINS.
